UNITED STATES PATENT OFFICE.

HIRAM J. WELLS, OF NASHVILLE, TENNESSEE.

PUMP.

SPECIFICATION forming part of Letters Patent No. 389,031, dated September 4, 1888.

Application filed January 21, 1888. Serial No. 261,509. (No model.)

To all whom it may concern:

Be it known that I, HIRAM J. WELLS, of Nashville, Davidson county, State of Tennessee, have invented a new and useful Improvement in Pumps, of which the following is a specification.

This invention pertains to improvements in pumps, having for its object to purify and remove extraneous substances from the water as it is being pumped for use; and the invention consists of certain combinations of parts, including their construction, substantially as hereinafter more fully set forth; and pointed out in the claims.

15 In the accompanying drawings, Figure 1 is a sectional elevation of my pump, showing it as applied for use. Fig. 2 is an inverted view of the cover removed from the pump-cylinder, and Fig. 3 is a horizontal section through 20 the same in its normal position.

In the embodiment of my invention I employ a chamber or cylinder, A, about centrally from the bottom of which depends a short semi-cylindric tube, a, with its lower or 25 bottom end closed, while in its straight side is arranged an outwardly opening air-valve, a', normally held closed by a light or weak spring, a'', fastened at one end to said tube and bearing at its free end upon said valve. In the upper end of the chamber or cylinder A is set or placed a cover, B, which consists of a top 30 plate, b, and a bottom, B^x, secured to a cylindric outer and inner wall, b² b³. The top plate, b, projects beyond the outer wall, b², thus serving as a flange to rest upon the upper edge of the cylinder A and support the cover in position. The inner wall, b³, forms a tubular or cylindric passage, b⁴, through the cover, which passage at its lower or inner end communicates with the interior of the cylinder A, while into the upper or outer end of the said passage is inserted the lower end of a tube or cylinder, b⁵, forming a continuation of said passage, which serves as the outlet or discharge 45 for the water from the cylinder A.

The bottom B^x of the cover B consists of a plate, b⁶, which rests against the lower edge of the inner wall or tubular passage b⁴, and has an aperture or orifice corresponding with said 50 passage, and is provided at its outer edge with a downwardly-projecting annular flange, b⁷.

The lower edge of the flange b⁷ itself is formed or provided with a horizontal outwardly-extending flange or plate, b⁸, which is connected or united at its outer edge with the lower edge 55 of the outer wall, b², of the cover. By reason of this form of connection of the bottom plate, b⁶, with the cover B the said plate is preferably disposed a short distance inwardly from the lower edge of the cover, while the bottom 60 edge of the outer wall of the cover is broadened. The lower end of the tube or passage b⁴ opens through a coincident aperture or orifice, e, in the bottom plate, b⁶, and across this orifice is disposed a support, c', which is secured 65 at its ends to said bottom plate. d is a valve which is centrally connected at opposite points near its outer edge to the support c', and is thus adapted to have two leaves which close the lower end of the passage or tube b⁴ and 70 open upwardly into the latter.

Through the cover B also passes another tube, B', preferably of a coincident curvature with the cylindric side walls of the cover and projecting through and a short distance above 75 the top plate, b, which projecting end is covered with a foraminated plate, forming a filter, B². The lower end of the tube B' opens through a coincident orifice or aperture in the bottom plate, b⁶, which orifice or aperture is 80 covered by a valve, e, secured at its ends to the said plate and at its one edge at the middle to the support c' and opening downwardly. A spring, e', secured to said support at one end, presses at its opposite end upon and normally holds said valve closed. 85

C is a plunger-tube, which passes through an orifice in the center of the support c', and is connected at its upper end to the usual handle, D, supported upon an arm or bracket projecting from the pump-stock. In the upper portion of the plunger-tube C is a series of air inlets or perforations, f, f', while to the lower end of said tube is applied the plunger or diaphragm C', as is also a valve, g, covering the 90 said end of the tube and opening downward against the action of a spring, g', one end of which is connected to said plunger or diaphragm and presses upon said valve. In practice the cylinder A is connected to the lower 95 end of a pump within the well or cistern by fitting the upper end of the tube b⁵ thereon.

In operation, water having been admitted by a previous downward stroke of the plunger in a filtered state through the filter B^2 past the valve c into the cylinder A , it will be seen that upon the upward stroke of the plunger air is admitted through the apertures f^1 into the plunger-tube C , after which it leaves said plunger-tube past the valve g and enters the cylinder A , filling the chamber below the plunger, where it remains until the plunger makes its return-stroke. Simultaneous with the upward movement or stroke of the piston the water previously admitted, as stated, to the cylinder A above the plunger C is carried or forced up into the tube b^3 past the valve d , from which it is discharged in the usual way. Now, upon the return or downward stroke of the plunger, the confined air in the chamber below the plunger will be forced or driven out of the cylinder A past the valve a' into the cistern or well, and into contact with the water therein, having the effect to agitate and purify it, driving off gases.

It will be seen that this invention is applicable to any pump, and embodies the feature of forcing air into the water in order to purify it during the pumping operation, while it also furnishes a filter to remove sediment or extraneous substances.

Having thus described my invention, what I claim as new is—

1. In a pump, the combination, with the cylinder provided with an air-valved outlet at its

lower end, of the cover provided with a valved tube or cylinder at its upper end and the plunger having a tubular rod provided at its upper end with a series of air-inlets and at its lower end with a valve, substantially as and for the purpose set forth.

2. In a pump, the combination, with the cylinder provided at its lower end with a valved outlet and at its upper end with a cover having a central valved passage and a filter at one side of said passage, of a tube or cylinder applied to the said cover and adapted for connection to a pump-barrel, and the plunger having a tube adapted for connection to the pump-handle, and provided in its upper end with a series of air-inlets and with an air-valved outlet at its lower end, substantially as set forth.

3. In a pump, the combination, with the cylinder provided at its lower end with a valved outlet and at its upper end with a cover having a central valved passage, and at one side of said passage a filter having a valved lower end, of a tube or cylinder applied to said cover and adapted for connection to a pump-barrel, and the plunger having a tube adapted for connection to the pump-handle, and provided in its upper end with a series of air inlets and at its lower end with an air-valved outlet, substantially as set forth.

HIRAM J. WELLS.
